WILD BIRD STATION

Norvel H. Jones, Miami, Fla.

Application June 7, 1954, Serial No. 30,839

Term of patent 14 years

(Cl. D31—2)

To all whom it may concern:

Be it known that I, Norvel H. Jones, a citizen of the United States, residing at Miami, county of Dade, and State of Florida, have invented a new, original, and ornamental Design for a Wild Bird Station, of which the following is a specification, reference being had to the accompanying drawing, forming a part thereof.

Fig. 1 is a perspective view of a wild bird station embodying my new design; and

Fig. 2 is an elevational view.

I claim:

The ornamental design for a wild bird station, as shown.
